CLAIM

The ornamental design for a handgun slide as shown and described.

DESCRIPTION

FIG. 1 is a top, front, and left-side perspective view of a handgun slide, showing our new design;

FIG. 2 is a top, rear, and right-side perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof; and,

FIG. 8 is a bottom plan view thereof.

Broken lines represent features that form no part of the claimed design.

1 Claim, 6 Drawing Sheets(56)
